US0D1104096S

(12) **United States Design Patent** (10) **Patent No.:** **US D1,104,096 S**
(45) **Date of Patent:** **** Dec. 2, 2025**

(54) **POWERED EXOSKELETON**

(71) Applicant: **Hypershell Co., Ltd.**, Shanghai (CN)

(72) Inventor: **Kuan Sun**, Shanghai (CN)

(73) Assignee: **Hypershell Co., Ltd.**, Shanghai (CN)

(**) Term: **15 Years**

(21) Appl. No.: **29/947,783**

(22) Filed: **Jun. 18, 2024**

(51) LOC (15) Cl. **24-02**

(52) U.S. Cl.

USPC **D24/190**; D15/199

(58) **Field of Classification Search**

USPC D3/5, 6, 7, 8, 9, 10; D15/199; D24/164,
D24/190

CPC A61F 5/0102; B25J 9/104; B25J 9/106;
B25J 9/109; B25J 9/0006; B25J 17/0241;
B25J 19/02; Y10T 74/20317; Y10T
74/20323

(57) **CLAIM**

The ornamental design for a powered exoskeleton, as shown and described.

DESCRIPTION

FIG. 1 is a front, right, and top perspective view of a powered exoskeleton showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The broken lines in the drawings illustrate portions of the powered exoskeleton that form no part of the claimed design.

1 Claim, 8 Drawing Sheets
